UNITED STATES PATENT OFFICE

2,461,546

SPINNING RING AND TRAVELER

Harvey E. Herr, Buffalo, N. Y., assignor to Herr
Manufacturing Company, Inc., Buffalo, N. Y.,
a corporation of New York

Application December 13, 1945, Serial No. 634,680

3 Claims. (Cl. 57—120)

1

This invention relates to certain new and useful improvements in spinning rings and travelers employed in connection with spinning machines.

It has for one of its objects to so design and construct the ring and the traveler wherein the bearing faces of the ring are so disposed as to provide for an upward and outward thrust or pressure of the traveler against the ring at all times to counteract or eliminate any tendency of the traveler to jump up and down on the ring during the spinning operation and accordingly insure a smooth running traveler and uniform thread tension.

Another object of the invention is to provide a ring and traveler construction wherein the traveler-engaging portion of the ring is substantially frusto-conical in cross section to provide an upwardly and outwardly extending inner bearing face and downwardly-facing annular shoulders at the inner and outer sides of the ring, and wherein the traveler is complementary in shape to engage the inner bearing face and adjoining inner shoulder during its operation about the ring, while the remaining portion thereof is free from contact with the ring to provide ample space for the movement of the thread.

Other features of the invention reside in the construction and arrangement of parts herein-after described and particularly pointed out in the appended claims.

In the accompanying drawings:

Figure 1 is a top plan view of the ring and traveler in place on the ring holder. Figure 2 is an enlarged sectional side elevation thereof. Figure 3 is an enlarged side view of the traveler.

Similar characters of reference indicate corresponding parts throughout the several views.

Referring now to the drawings, 10 indicates the holder which is adapted to be mounted on the traverse bar of a spinning machine, and 11 indicates the spinning ring which is detachably applied to the holder and upon which the traveler 12 revolves. The holder may be ring-like in form with its opening 13 adapted to receive the lower portion of the spinning ring in a snug fit, and it has slotted attaching flanges projecting outwardly therefrom for detachably securing the holder to the traverse bar. Formed integrally with the holder at one side thereof is a lubricant-receiving well 14.

The upper or traveler-engaging portion of the ring is preferably of frusto-conical shape in cross section to provide an inner bearing face 15, a top face 16 and inner and outer lower faces or

2

downwardly-facing annular shoulders 17 and 18, respectively. The inner bearing face of the ring extends upwardly and outwardly from the inner lower face thereof, the latter and the top face 16 being substantially horizontal or extending in planes at right angles to the ring-axis.

The traveler 12 is made from a single piece of wire and is complementary in shape to the head or bearing portion of the ring to fit thereover in the manner shown in Figure 2. Its legs 19 are straight and downwardly diverging in symmetrical fashion, paralleling the companion side faces of the ring, and each terminates at its lower end in an inwardly-bent foot 20 for disposition beneath the annular shoulders 17, 18 of the ring. The upper looped or vertex portion of the traveler is fully rounded, as indicated at 21, to provide ample clearance between it and the flat top side of the ring for the passage of the thread. During the operation of the traveler, the inner leg is adapted for straightwise engagement with the inner bearing face 15 of the ring while the foot 20 thereof engages the underside of the companion lower bearing face 17. The complementary leg and its foot, during such operation, assume a position free from contact with the outer side of the ring and the companion lower face 18. This running position of the traveler is caused by the inner bearing face of the ring which exerts a constant upward and outward thrust on the traveler and results in an even and uniform thread-tension.

For the purpose of lubricating the bearing face 15 of the ring, I provide the lower portion of the ring contained within the holder 10 with an annular lubricant-receiving channel 22 communicating with the well 14 through a duct 23 and with the bearing face of the ring through one or more discharge ports 24 each containing a wick 25 for regulating the feed of the lubricant to such bearing face.

I claim as my invention:

1. A device of the character described, comprising a spinning ring having a traveler-engaging portion of substantially frusto-conical shape in cross section providing a downwardly-facing lower bearing face disposed at right angles to the ring-axis and an inner bearing face extending upwardly and outwardly from the inner edge of said lower bearing face, and a traveler of complementary shape having legs paralleling the side faces of the ring and joined at their upper ends in a curved vertex portion spanning the top side of the ring to provide a thread-engaging loop, the inner traveler leg being engageable straight-

wise and coextensively with the inner bearing face of the ring and both legs terminating at their lower ends in opposing feet, the foot of the inner traveler leg being horizontal and engageable with the lower bearing face of the ring.

2. A device of the character described, comprising a spinning ring having a traveler-engaging portion of substantially frusto-conical shape in cross section and terminating at the base of such portion at the inner and outer sides thereof in lower bearing faces disposed at substantially right angles to the ring-axis, the inner bearing face of the ring extending upwardly and outwardly from the inner edge of the adjoining lower bearing face, and a traveler of complementary 15 shape having legs disposed in parallel relation to the side faces of the ring and joined at their upper ends in a curved vertex portion spanning the top side of the ring to provide a thread-engaging loop, each of said legs terminating at its 20 free end in an inwardly-bent horizontal foot for disposition beneath the companion lower bearing face of the ring.

3. A spinning ring for a traveler, comprising a ring-body including a traveler-engaging portion of frusto-conical shape in cross section providing an upwardly and outwardly extending flat traveler bearing face at the inner side thereof, the base of such traveler-engaging portion having downwardly-facing shoulders disposed at right angles to the ring-axis.
